UNITED STATES PATENT OFFICE.

ROBERT E. McELDONNEY, OF NEW MARTINSVILLE, WEST VIRGINIA, ASSIGNOR TO
NEW MARTINSVILLE GLASS MFG. CO., OF NEW MARTINSVILLE, WEST VIRGINIA,
A CORPORATION OF WEST VIRGINIA.

DESIGN FOR A CONSOLE BOWL OR SIMILAR ARTICLE.

Application filed July 25, 1928. Serial No. 27,580. Term of patent 3½ years.

To all whom it may concern:

Be it known that I, ROBERT E. McELDONNEY, a citizen of the United States, residing at New Martinsville, in the county of Wetzel, State of West Virginia, have invented a new, original, and ornamental Design for a Console Bowl or Similar Article, of which the following is a specification, reference being had to the accompanying drawing, forming part thereof.

Figure 1 is a perspective view of a console bowl or similar article, showing my new design.

Figure 2 is a plan view of Figure 1.

I claim:—

The ornamental design for a console bowl or similar article, as shown.

ROBERT E. McELDONNEY.
